UNITED STATES PATENT OFFICE

153,486

DESIGN FOR A TOY ANIMAL FIGURE

Katharine Wood, Staten Island, N. Y.

Application March 20, 1947, Serial No. 137,762

Term of patent 14 years

(Cl. D34—2)

To all whom it may concern:

Be it known that I, Katharine Wood, a citizen of the United States, residing at Staten Island in the county and Borough of Richmond and State of New York, have invented a new, original, and ornamental Design for a Toy Animal Figure, of which the following is a specification, reference being had to the accompanying drawing, forming part thereof, in which

Fig. 1 is a side view of the toy animal figure from the front end, and

Fig. 2 is a side view of the toy animal figure from the tail end, showing my new design.

I claim:

The ornamental design for a toy animal figure, as shown.

KATHARINE WOOD.
